S. OLSZOWIEC

GUN

Filed April 22, 1924

INVENTOR
Stanislaw Olszowiec

BY
John H. Pelech
ATTORNEY

UNITED STATES PATENT OFFICE.

STANISZLAW OLSZOWIEC, OF NEW WATERFORD, NOVA SCOTIA, CANADA.

GUN.

Application filed April 22, 1924. Serial No. 708,111.

To all whom it may concern:

Be it known that I, STANISZLAW OLSZOWIEC, a citizen of the United States, residing at box 351, New Waterford, in the Province 5 of Nova Scotia and Dominion of Canada, have invented certain new and useful Improvements in Guns, of which the following is a specification.

This invention relates generally to guns 10 or rifles, the invention having for an object the provision of an electrically operated firing pin whereby the user of the gun is relieved of the strain incidental to the drawing back of the pin.

15 For further comprehension of the invention, and of the objects and advantages thereof, reference will be had to the following description and accompanying drawing, and to the appended claims in which the 20 various novel features of the invention are more particularly set forth.

Fig. 1 of the drawing is a fragmentary longitudinal sectional view of a gun having the invention applied thereto.

25 Fig. 2 is a fragmentary plan view.

Fig. 3 is a detail plan view of the circuit closing arm.

Referring now to the drawing, the gun here shown is of the type in which the 30 breech of the barrel is exposed by swinging the stock upon the barrel. The barrel is here shown at 10, the lock portion 11 of the gun being hinged thereto as at 12, the stock being indicated at 13. It will be understood of course that the usual mechanism 35 will be applied to the lock to hold it in place.

According to my invention, I mount in the part a solenoid 15 whose plunger 16 constitutes the firing pin, the plunger being 40 guided in a suitable longitudinal passage in the part 11. Connected to the rear end of the plunger is a brass rod 17 which extends through the solenoid and projects from the rear end of the latter and is surrounded at its rear end by a coiled tension 45 spring 18 connected at one end to the solenoid at its opposite end to the said rod, this spring acting to urge the plunger forward to explode the cartridge. For energizing the solenoid I mount in a suitable cavity in the stock 13, to which cavity entrance may be had from the butt end of the stock, an electric battery 20 whose terminals are adapted to abut against the contact members 50 21, 22 in the front end of the stock through which the current is supplied to the solenoid.

15 As here shown these members 21, 22 project adjacent other members 23, 24 which are adapted to be lifted into contact therewith by the pins 25, 26 held in place by the 60 flat springs 27, 28 fixed at one end on opposite sides of the part 11. The member 23 connects with one terminal of the solenoid coil, while the member 24 connects to a spring contact 30 mounted adjacent a fixed 65 contact 31 to which the other end of the solenoid coil connects.

To cause the contact spring 30 to be moved against the contact 31 and so energize the solenoid, I provide the following means: 70 Pivoted at one end to the part 11 as at 35 is an arm 36 which has its opposite, or free end engaging under the contact 30 so that when this arm is swung upward the said contacts will be closed. This arm is formed, 75 adjacent its pivoted end with a longitudinal slot 37 which extends somewhat less than one-half the length of the arm. At the rear end of this slot an angular wall element 38 is formed, the lower portion of this wall 80 element being adapted to be engaged by the end of a pin 39 slidable in a socket 39' in an offset 40' from a trigger element 40 pivoted as at 41 in the part 11 and urged forwardly by a spring 42 coiled around its 85 hinge pintle and connected at opposite ends respectively to said trigger element and the part 11. The pin 39 is urged rearwardly in the socket by means of a spring 44 located in said socket behind the pin, rearward 90 movement of the pin being limited by means of a crosspin 45 therein engaging in slots such as 46 in the said offset 40'.

When the gun is to be fired, the members 27, 28 are compressed, and trigger 40 is 95 pulled backward. The pin 39 engages the inclined lower part of the wall element 38 and moves the arm 36 upward to move the contact 30 against the contact 31, the spring 44 in the part 40' being strong enough to 100 resist backward movement of the pin while the contacts are being closed. The circuit to the solenoid being closed the plunger is drawn back. Upon further rearward movement of the trigger, the arm 36 being 105 stopped by the fixed element 31, the pin 39 is moved inward until it rides over the apex of the angular wall 38, when the arm 36 falls and the circuit is opened. When the trigger is released it is returned to normal position by the spring 42, which latter 110 is of sufficient strength to cause the com-

pression of the spring 44 as the pin 39 swings downward over the top part of the wall element 38. To limit the rearward movement of the plunger 16 to any desired extent I may mount on the side of the part 11 a screw 50 over which is slipped a collar having a finger 52 projecting through a slot 53 in the side of said part 11 to engage behind the rod 17, a pair of nuts 54 being threaded on the screw on opposite sides of the collar to lock it in adjusted positions.

While I have illustrated and described a preferred embodiment of my invention it is to be understood that I do not limit myself to the precise construction herein shown, and that various changes and modifications might be made therein without departing from the spirit and scope of the invention as defined in the appended claims.

Having thus described my invention what I claim as new and desire to protect by Letters Patent of the United States is as follows:

1. In a gun, a barrel, a solenoid, a firing pin constituted by the plunger of the solenoid, a spring urging said plunger rearward and adapted to be tensioned when the plunger is moved by energizing of the solenoid, a battery, contact elements controlling the circuit from said battery to said solenoid, and a trigger element for closing said contacts, and means for adjustably limiting the movement of the plunger by the solenoid.

2. In a gun, a barrel, a solenoid, a firing pin constituted by the plunger of the solenoid, a

spring urging said plunger rearward and adapted to be tensioned when the plunger is moved by the solenoid, a battery, contact elements controlling the circuit from the battery to the solenoid, said contact elements comprising a spring contact and a fixed contact adjacent thereto, an arm pivoted at one end in the gun, and a trigger element adapted to engage said arm to move it to cause said spring contacts to be closed.

3. In a gun, a barrel, a solenoid, a firing pin constituted by the plunger of the solenoid, a spring urging said plunger rearward and adapted to be tensioned when the plunger is moved by the solenoid, a battery, contact elements controlling the circuit from the battery to the solenoid, said contact elements comprising a spring contact and a fixed contact adjacent thereto, an arm pivoted at one end in the gun, and a trigger element adapted to engage said arm to move it to cause said spring contacts to be closed, said trigger element having mounted thereon a spring-pressed pin adapted to engage an angular element on the said arm, said pin being adapted to first move said spring contact into engagement with the fixed contact, and upon continued movement of the trigger element to ride off said angular element to free the said arm and allow the said spring contact to move away from the fixed contact.

In testimony whereof I have affixed my signature.

STANISLAW OLSZOWIEC.
